TORWALD WINTER, OF BOSTON, MASSACHUSETTS.

Letters Patent No. 79,174, dated June 23, 1868.

IMPROVED RECUMBENT CHAIR.

The Schedule referred to in these Letters Patent and making part of the same.

TO ALL WHOM IT MAY CONCERN:

Be it known that I, TORWALD WINTER, of Boston, in the county of Suffolk, and State of Massachusetts, have invented an Improved Recumbent Chair; and I do hereby declare that the following, taken in connection with the drawings which accompany and form part of this specification, is a description of my invention sufficient to enable those skilled in the art to practise it.

My invention relates to the construction of that kind of chairs known as railway or recumbent chairs, which are adapted to sustain and support the body in easy position, whether the person in the chair be sitting erect or be leaning back at any angle, down to an extended or nearly horizontal position, the parts of the chair moving with the person, so that the whole length of body is supported at any position the person may assume.

My improvement consists in the peculiar arrangement of the arms, leg-rest, and back, with mechanism for locking them in position.

The drawings represent, at A and B respectively, a side elevation and a front view of a chair or chair-frame embodying my improvement.

a denotes the stationary base; b, the back, jointed to the rear of the base, as shown at A, and having jointed to each of its uprights an arm, c, the front end of which is jointed to and supported by a lever, d, fulcrumed in the top rail e of the base, a. Each lever d extends through its rail e, and the lower ends of the pair are connected by a cross-bar, f. At the centre of this bar is an arm, g, which projects under the front rail h, and is jointed at its front end to a leg-support or frame, i, which frame is hung at top to the front ends of the side rails e of the base, a, as shown at B. At the bottom this frame is a foot-board or rest, k, hinged upon arms l, projecting from the bottom rail m of frame i, the foot-rest swinging down against the arms, as seen at A, or up over them, as seen by the red lines at A. n denotes a curved ratchet or rack-bar, hung upon a pin, o, the bar projecting through a slot, p, in the rail m, and having a foot-piece, q, at its front end. The bar also extends through a slot in a cross-rail, r, (seen in dotted lines at A,) and its notches, s, catch into a tooth at the bottom of this slot, the bar being pressed down by a spring, t, so that in whatever position the leg-rest may be brought, one of the notches of the rack engages with this tooth, and thereby holds the leg-rest stationary.

The parts being thus constructed and arranged, the operation of the chair will be readily understood. The chair being in upright position, as seen in color at A, when the sitter wishes to recline he places a foot on top of the piece q, and depresses said piece, thereby freeing the rack-notch from the catch or tooth on rail r. He then leans-back, keeping his foot on piece q, and presses back the back frame b, the movement of which is communicated by arms c and levers d to the leg-rest i, tipping up such rest as the back is depressed, the movable parts being brought to a stop, and being locked in position at any point, by releasing the foot-piece q, the rack being sprung back into engagement with its catch at such release. By this means, and without any movement of the seat, the chair may be extended so as to bring the seat, leg-rest, and back, into or nearly into horizontal line, as seen by the red lines at A, and when the chair is thus extended the foot-board k may be tipped up, as also seen in red at A.

It will be seen that this construction is very strong, that the parts cannot easily get loose or out of place, that the arrangement is simple and inexpensive, that the arrangement of the parts which move is such as to offer no impediment to upholstering the chair, and that the chair is readily brought to and locked in any required position without use of the hands.

Instead of connecting the levers d by cross-bar f, and arm g to the leg-rest or frame i, the connection may be made by links jointed to the lower ends of levers and the ends of the leg-rest, but I prefer the arrangement shown.

I claim the combination of the stationary base and seat-frame a, tipping back b, jointed arms c, levers d, leg-rest i, spring-rack bar n, and its foot-piece q, when all are arranged to operate together, substantially as shown and described.

I also claim, in combination with the above, the foot-piece k, arranged to swing down against or up from the arms l, substantially as shown and described.

TORWALD WINTER.
